N. WOOLSEY.
NEEDLE PLATE FOR SEWING MACHINES.
APPLICATION FILED OCT. 30, 1907.

922,744.

Patented May 25, 1909.

UNITED STATES PATENT OFFICE.

NAOMI WOOLSEY, OF LOS ANGELES, CALIFORNIA.

NEEDLE-PLATE FOR SEWING-MACHINES.

No. 922,744.

Specification of Letters Patent.

Patented May 25, 1909.

Application filed October 30, 1907. Serial No. 399,961.

To all whom it may concern:

Be it known that I, NAOMI WOOLSEY, a citizen of the United States, residing at Los Angeles, in the county of Los Angeles and 5 State of California, have invented a new and useful Needle-Plate for Sewing-Machines, of which the following is a specification.

An object of this invention is to provide for sewing-machines a superior attachment 10 of that class of devices whereby such machine can be made efficient for making embroidery, Spanish drawn-work, and Battenberg work, and for darning broken or worn fabrics.

The invention may be embodied in different 15 forms, and I shall illustrate the same in two forms which are capable of use on rotary sewing-machines, although I do not propose to limit the invention to any specific form or construction in which it may be 20 embodied.

The invention comprises a sewing-machine 25 needle-plate provided underneath with a recess and with a tubular thread-guide extending downwardly through and surrounded by a recess and arranged coaxially with relation to and forming an extension of the needle-hole of the plate; said plate being constructed and adapted to be connected with the bed-plate of a sewing-machine and to form above 30 said bed-plate a protuberance having a sloping rim. Said protuberance may be formed as a projection from the top surface of the plate, or it may be formed by the plate itself, the edges of said plate being beveled to form 35 the sloping rim of the protuberance.

The accompanying drawings illustrate the invention.

Figure 1 is a fragmental view of a sewing-machine provided with the invention in one 40 form of embodiment deemed preferable for general work. Fig. 2 is a like view of a machine provided with the improvement in a form of embodiment more especially adapted for silk embroidery. Fig. 3 is a longitudinal section 45 on line x^1-x^2 , Figs. 4 and 5, of the form shown in Fig. 1. Fig. 4 is a section taken at right angles to the section in Fig. 3, on line x^3 , Figs. 3 and 5. Fig. 5 is a bottom view of the form shown in Figs. 1, 3 and 4. Fig. 6 is 50 a section on line x^6 , Figs. 7 and 8, of the plate shown in Fig. 2. Fig. 7 is a section on line x^7 , Figs. 6 and 8. Fig. 8 is a plan view of the plate shown in Fig. 2.

This newly-invented needle-plate comprises 55 an upwardly projecting plate 1 having a beveled rim 2 and adapted to support the

embroidery or other material, not shown, to be operated upon, and is provided with a needle-hole 3 and with a recess 4 surrounding a downwardly-extending tubular thread-guide 5. Said recess 4 is of appropriate dimensions to chamber that portion of the feed 6 of the sewing-machine which usually projects above the surface of the sewing-machine bed-plate 7. Said tubular thread-guide extends downward through the usual slot 8 in the feed so that no obstruction is offered to the operation of the feed.

In practice, when it is desired to use the sewing-machine for doing embroidery work, 70 Battenberg work, or the like, the presser-foot and the needle-plate, not shown, will be first removed from the machine. Then the newly-invented needle-plate will be placed in position with the beveled rim upward and 75 the recess in position to receive the feed, while the tubular thread-guide extends down through the slotted feed. The needle-plate will then be secured in place by suitable means, as screws 9 inserted through holes in 80 the needle-plate. When this is done, the machine is ready for operation, whereupon the fabric or other body upon which the embroidery is to be made will be brought into position over the needle-plate and will be 85 moved to and fro as may be necessary for doing the work.

In the form shown in Figs. 1, 3, 4, and 5, the beveled rim 2 is approximately co-extensive with the rim of the plate itself, the 90 edges of which are beveled, sloping gradually from the face of the plate to the base of the plate thus to allow the embroidery, and so forth, to be moved freely over the same without catching.

In the form shown in Figs. 2, 6, 7 and 8, a projection 11 of comparatively small dimensions, is provided on the face of the plate in the form of a protuberance in the midst of a face of considerable extent which surrounds 100 said protuberance, the sides of the protuberance sloping gradually to the plain face 10. The purpose of this construction is to cause an upward bulge in the portion of the embroidery which is being directly operated 105 upon and to hold the same above the level of the rest of the embroidery. By this construction the work of embroidering is greatly facilitated. The projection is in the form of a protuberance 11 which is preferably elongated.

Preferably, a portion of the margin of the

plate is semicircular, as shown at 12, and in the form of plate shown in Fig. 1 a recess 13 is provided to fit over the edge of the bed-plate 7, and the edges of the needle-plate are 5 rounded and sloped, as shown at 14, so that the material of the work, not shown, will not catch on any of the edges.

The purpose of the tubular thread-guide 5 is to carry the thread down below the teeth 10 or points of the feed 6 so that there is no danger of the thread loops being caught by the teeth or points of the feed, and so as to insure that the loop will be caught by the under thread. In practical use, by providing 15 the plate constructed as set forth, the operator can move the embroidery or other fancy work freely without any liability of catching, and the work is greatly facilitated as compared with the use of former devices 20 in which the protuberance formed by the plate has been of an angular character.

What I claim is:—

1. A needle-plate for sewing-machines comprising a plate having a needle-hole and having a recess in its lower face around the needle-hole, and a tubular thread-guide extending downwardly from the plate through the recess and forming an extension of the needle-hole.
2. A needle-plate for sewing-machines comprising a plate having a protuberance extending upwardly and having a needle-hole centrally located through the protuberance and having a recess in its lower face

around the needle-hole and a tubular thread-guide extending downwardly through the recess and forming an extension of the needle-hole.

3. In a sewing-machine, the combination with the bed-plate, of a needle-plate having a needle-hole and having a recess in its lower face around the needle-hole and a tubular thread-guide extending downwardly from the plate through the recess and forming an extension of the needle-hole, said tubular thread-guide extending into the slot of the feed to protect the thread from the action of the feed.

4. In a sewing machine, the combination with the bed-plate and slotted feed, of a needle-plate having an upwardly-extending protuberance and having a needle-hole through the protuberance and having a recess in the lower face of the protuberance around the needle-hole, a tubular thread-guide extending downwardly from the protuberance through the recess and forming an extension of the needle-hole, said tubular thread-guide operating in the slot of the feed to protect the thread from the action of the feed.

In testimony whereof, I have hereunto set my hand at Los Angeles, California, this 24th day of October, 1907.

NAOMI WOOLSEY.

In presence of—

JAMES R. TOWNSEND,
TILLIE E. ADAM.
